PAGE END SIGNALING MEANS FOR TYPE-WRITERS, BILLING MACHINES, AND THE LIKE

Frank S. Hassell, Jr., Washington, D. C.

Application July 26, 1946, Serial No. 686,419

23 Claims. (Cl. 197—189)

1

This invention relates to typewriters, billing machines and the like, and particularly to novel and improved means and method for page end signaling in the operation of such machines.

One object of the invention is to provide a device for such a machine which can be quickly and easily set to give an audible signal just before reaching a predetermined point on the page being typed.

Another object of the invention is to provide a simple device which can be attached easily to any make conventional type standard or portable typewriter, billing machine or other similar machine without the necessity of using tools, and without either altering the said device or altering any part of the machine.

Another object of the invention is to provide such a device which will visibly indicate to the typist at any time while typing the page exactly how many lines remain either before she reaches a predetermined point on the page or before she reaches the last writing line on the page.

A further object is to provide a bell signaling device which does not require the conventional type clapper or hammer to strike same, but a device permitting the use of a metal ball, ball retainer and gong and using the force of gravity in combination with the foregoing to fit special needs such as the invention outlined herein and to simplify and reduce the number of working parts comprising the bell.

An additional object of the invention is to provide a device that will accomplish the foregoing which is durable, very simple with few working parts and inexpensive to manufacture.

Another object of the invention is to provide a device with all the above features which will be constructed and attached so that it will not interfere with the normal operation of the typewriter.

With these and such other objects in view as will appear hereinafter, this invention comprises the construction, combination and arrangements of parts hereinafter described with reference to the accompanying diagrammatic drawings exemplifying embodiments thereof and forming a part of the invention.

For a better understanding of the invention reference may be had to the accompanying drawings wherein—

Fig. 1 is a perspective view of one embodiment of the invention;

Fig. 2 is a perspective view of a letterhead and a guide which the typist may use if desired with the means shown in Fig. 1;

2

Fig. 3 is a longitudinal sectional view of the means shown in Fig. 1;

Fig. 4 is a sectional view along the line 4—4 of Fig. 3;

Fig. 5 is a sectional view along the line 5—5 of Fig. 3;

Fig. 6 is a sectional view along the line 6—6 of Fig. 3;

Fig. 7 is a sectional view along the line 7—7 of Fig. 6;

Fig. 8 is an exploded view of the parts forming the above embodiment of the invention;

Fig. 9 is a view of the above embodiment embodying an adapter for a different sized head or typewriter knob;

Fig. 10 is a perspective view of the adapter;

Fig. 11 is an elevational view, partly in section, of another modification of the invention;

Fig. 12 is a front view thereof;

Fig. 13 is a sectional view, somewhat enlarged, along the line 13—13 of Fig. 11;

Fig. 14 is a sectional view, somewhat enlarged, along the line 14—14 of Fig. 12;

Fig. 15 illustrates another embodiment of the invention;

Fig. 16 illustrates a further embodiment of the invention; and

Figs. 17 and 17A illustrate a further embodiment of the invention.

Referring to the drawings, I have illustrated my invention as applied to a typewriter, a billing machine or the like, indicated generally by the numeral 1 and embodying a conventional platen 2, the latter being mounted on a conventional

shaft 3 for rotation step by step properly to space the lines as the typing proceeds. The shaft 3 carries at its end a conventional hand knob or head 4 which may be gripped by the typist to rotate the platen 2 and adjust the paper sheets 40 in the machine for the beginning of the typing operation.

In the conventional machine no means are provided for signaling or giving any indication to the typist of the approach to the end of the page or of the approach to that part of the page where it is desired to discontinue the typing.

My invention resides in the embodiment illustrated in Figs. 1—8 inclusive in a means indicated generally by the numeral 5, which signals audi-

bly or otherwise the typist when any desired point in the page being typed is reached, as, for example, from one to three lines before the page has reached a point or line previously decided upon or determined by the typist. Moreover, at 55 any time while the paper is in the machine and

is being typed, the device indicates to the typist the number of lines remaining before she reaches either a line previously determined or the end of the page. Moreover, the means 5 is readily attachable to and detachable from the machine with the greatest facility and in the particular embodiment shown the means 5 is mounted upon the knob or head 4 of the platen 2 in an easily attachable and detachable manner whereby within a few seconds the device may be attached by hand without the aid of any tool to any model or make of conventional standard or portable typewriters, billing machines and similar machines without any alteration whatever of the machine. This means may be with equal facility detached from the machine or, as will hereinafter appear, the signaling and indicating means may be rendered inoperative or operative at any time by the typist.

More specifically, the invention comprises a compact unit 5 which is carried by the knob or head 4 of the platen, the whole attachment being so small as to form only a short extension of the shaft 3 beyond the knob 4. It comprises essentially three parts, namely, an attaching means 10 for attachment to the knob 4, a gong or similar device 11, and an indicator 12 which, during the typing operation, rotates with the platen 2, attaching means 10, and the gong 11, and which may be manually swiveled or rotated independently of the platen 2 to make the desired adjustment for signaling to the typist when that part of the page is reached during the typing operation.

The gong 11 is cup-shaped and the cylindrical indicator 12 projects into this cup-shaped gong. The indicator 12 in the embodiment shown is of cylindrical shape and is made of transparent material as, for example, and preferably, of a plastic material of a character to have the desired strength and resistance to breakage. It is provided on its interior surface with a spiral track 13 for accommodating a ball indicator 14 whereby, as the platen and the means 5 are rotated in steps according to the line spacing, this ball indicator 14 is caused by gravity to traverse the spiral track 13. The cylinder 12 is mounted on a shaft 15 which passes longitudinally therethrough. The spiral track 13 is provided with side walls 13' of sufficient height or depth to prevent accidental displacement of the indicator ball 14 axially from one turn of the spiral track to the other. That is, the height of the track walls 13' cooperatively with the shaft 15 prevent such accidental displacement and accordingly the only movement of the ball indicator 14 is along the spiral track 13, either inwardly toward the gong 11 during the typing operation or outwardly therefrom during adjustment of the metal ball 14 to the desired position along the cylinder 12.

A scale is provided along the track 13 of the cylinder, the distance between the divisions of the scale corresponding to the distance the cylinder 12 moves in the direction of the spiral when the platen 2 is rotated a distance equal to the spacing of a line. This scale should comprise divisions in any number desired and visibly in the drawings are divisions from zero up to 75. This scale begins near the inner end of the cylinder 12 and follows the track 13 outwardly clockwise, looking towards the outer end of the cylinder. In the particular embodiment shown, this scale is incorporated on the outside of the cylinder and, as will be more particularly described hereinafter, the cylinder 12 is swiveled by hand on the shaft 75

15 independently of the platen 2 to adjust the metal ball 14 to that part of the scale on the track corresponding to that point on the page where the signal is to be given.

5 The signal is given when the metal ball 14 reaches a predetermined point in the spiral track 13 and, in the particular embodiment shown, this point in the track 13 is an outlet 16 passing radially outward from the track 13 through the shell 19 of the cylinder and in this embodiment this outlet 16 is disposed at a point having an arcuate distance from the zero mark of the scale which is equal to about a quarter of one complete revolution of the cylinder 12 about the axis determined by the shaft 15. There is mounted to rotate with the cylinder 12 a guide and retainer 17, this retainer being in the form of a short tube disposed in alignment with the outlet 16 in the cylinder and being adapted to guide the metal ball 14 as it drops by gravity through the outlet 16 to fall upon the gong 11 at that point in the typewritten page where the signal is to be given.

20 The setting of the means 5 for indicating the progress during the typing of the page and giving the signal at the end of the page is very simply effected as follows.

25 With the typing page or paper inserted in the machine so that the top portion of it can just be seen, the typist grasps the cylinder 12 with the hand and turns it independently of the platen 2 counterclockwise looking inwardly toward the gong, until the indicator ball 14 appears just below the number on the scale on the cylinder track at which the typist wishes to be signaled. That is, the cylinder is rotated counterclockwise for adjustment, assuming that the metal ball 14 is disposed between the scale number and the inner end of the cylinder or disposed at the inner end of the cylinder. If the ball should happen to be located at a scale number higher than a particular number at which the signal is to be given, naturally the rotation of the cylinder 12 would be clockwise to bring the ball to the desired number. This number corresponds to that part of the page at which or near which the typing is to be discontinued as measured against the scale by a ruler 20 or already known by the typist. This number on the cylinder can easily be observed between the ball and the shaft 12 at the typist's normal sitting position. She then proceeds to type the page and as she proceeds the cylinder 12 rotates with the platen 2 and accordingly the indicator ball 14 travels inwardly along the track 13 inwardly of the cylinder. At any time while the page or paper being written on is in the machine the typist can by glancing at the cylinder and the scale number centered between the ball and the shaft 15 observe the number of lines yet remaining on the sheet or page to be typed. The ball 30 moves horizontally inwardly along the casing of the cylinder and within the spiral groove 13 from right to left as the platen is turned during operation of typing. When the ball reaches the outlet 16 it drops by gravity as indicated above through the guide and retainer 17 to give the signal, and in the particular embodiment shown this signal is given by the ball striking the inner surface of the gong 11. It is understood that the metal ball 14 can move freely relatively to the spiral track 13 so as to always assume a position at the bottom of the cylinder 12 and also that the guide or retainer 17 and the outlet 16 are of larger diameter than the ball 14 so as to facilitate the passage of the indicator ball 14 therethrough in both directions. In the particular embodiment shown

the guide 17 is of a diameter corresponding to the width of the track 13, which is slightly larger than the diameter of the metal ball 14.

In the particular embodiment shown the inner end of the spiral track 13 is provided at a point adjacent the outlet 16 with a ridge 18 which is high enough to retard the falling of the metal ball 14 through the outlet 16 for a turn of two or three scale numbers on the cylinder but not high enough to prevent the ball from tumbling over this ridge by gravity after an arcuate movement of the cylinder through two or three scale numbers. That is, the ball 14 is retarded by this ridge 18 for only a short arcuate distance indicated, whereupon it tumbles over into the outlet 16 and without hindrance from the shaft 15, since the distance between the ridge 18 and the shaft is larger than the diameter of the ball. This contributes towards accuracy in signaling.

From one to four scale lines as may be desired before reaching the predetermined point on the page at which the signal is to be given, the metal ball 14 plunges over the ridge 18 through the hole or outlet 16 to deliver the signal, and in the particular embodiment shown as indicated the signal is delivered by the impact of the ball against the gong 11 or the normal vibration of the means 5 while the typist continues to type subsequent to the initial plunge of ball 14 onto the gong 11 will ordinarily produce a signal of sufficient loudness. The ball as indicated is retained in the retainer 17. When the typist receives this signal she glances at the scale number on the cylinder just below the shaft 15 at the extreme lefthand of the spiral track 13. If, for example, the scale number is zero, she knows she has reached the end of that part of the page where the typing is to be discontinued. If the scale number is one, two, three or four, then she knows she lacks one, two, three or four scale lines, respectively, before reaching the predetermined stopping point on the page being typed. This variance of from one to four scale points is sometimes caused by the movement of the typewriter or other machine while in operation. For example, the operator who throws her carriage back with great force will usually have about three more lines to write after being signaled than the typist who moves the carriage back with less force. However, after becoming familiar with the device, which familiarity can be obtained with very little experience, the typist may make proper allowance for the extra lines in setting so that it will ring on the last line rather than one, two, three or four lines in advance.

However, being signaled a line or so in advance is no hindrance to the typist but on the contrary is advantageous because then she will be signaled before she inadvertently starts the first line of a paragraph on the last line of a page. Also, by glancing at the scale numbers on the cylinder, she can tell in a second exactly the number of lines remaining. After the first signal the ball continues to make a little noise on the gong, which constantly reminds the typist that she is near the bottom margin.

When for any reason the operation of the signal and indicating means is not desired as, for example, when the typist has one or more one-page letters to write or one or more short bills to write, she can render the signaling means inoperative. This is effected by a means 19 which is in the form of a curved plate or gate disposed on the outside of the cylinder 12 and adapted to occupy either a position between the outlet 16

and the retainer 17, thereby closing the outlet 16 and keeping the ball within the cylinder and preventing any further signaling, or to a position (that shown in full lines) where this gate is moved to a position to one side where it does not obstruct the passage of the ball 14 into the retainer 17. The means for supporting and actuating this gate 19 will be more particularly set forth hereinafter.

10 The scale of the ruler 20 of Fig. 2 corresponds to the scale on the track 13 of the cylinder 12 and by placing the ruler or tape 20 up against the sheet to be typed the typist can determine at a glance where the indicator ball 14 is to be set just before beginning the typing operation.

In the particular embodiment shown the cylinder 12 is provided with a back stop 21 immediately behind the outlet 16 which extends up high enough to prevent the metallic ball 14 from accidentally passing between the back stop 21 and the shaft 15.

20 Also the outer end of the cylinder or the outer end of the spiral track 13 is provided with a stop means 22 for blocking the outward travel of the ball and preventing it becoming wedged or caught in any way at the outer end.

25 The device comprising the three parts 10, 11 and 12 is mounted on the machine for ready attachment and detachment without disturbing or altering the machine in any way. This is effected

30 by the retaining means 10 which is in the form of a cup-shaped gripping and holding member and is formed of a slightly flexible and resilient material as, for example, of rubber, natural or synthetic, and the means 5 is readily attached to the machine by slipping the cup means 10 over the platen knob 4. This means 10 firmly frictionally

35 grips the knob 4 and accordingly means 10 rotates with the platen 2. This means 10 is provided with a roughened or corrugated surface 25

40 which enables the typist to rotate and adjust the platen 2 by hand at any time desired. The device 5 may be detached from the machine by simply slipping the cup-shaped member 10 off of the platen knob 4. This can be effected as above described very quickly and without disturbing or without the necessity for alteration of the machine.

The mounting of the parts 10, 11 and 12 of the device as a unit may be effected in any suitable manner. In the particular embodiment shown the three parts are assembled together as a unit by a means comprising a shaft 15 which has an enlarged inner end 15', a screw 26 which is screw-threadedly attached to the end of the

55 enlarged section 15' of the shaft, and a disc holding member 27. The latter is disposed within the cup-shaped holding member 10 and lies flat against the bottom of this member. In the particular embodiment shown it is of, roughly, the

60 same diameter as the platen knob 4. It is provided with a counter sunk hole in the center to receive the head of the screw 26 when the latter is screwed into the shaft section 15'. The outer end of the cylinder 12 is provided with a central

65 countersunk recess for the reception of a correspondingly shaped screw head of the shaft 15. The enlarged section 15' of the shaft is provided intermediate its ends with a recess or opening 28 for the reception of a holding pin 29 which fastens

70 a holding disc 30 to the enlarged section 15' of the shaft. This disc 30 is provided with a recess or opening 31 adapted to receive the fastening pin 29, the opening 31 passing radially through the holding disc 30 and registering with the recess 28 formed in the shaft section 15'. The gong

It is disposed against the holding disc 30 on one side and against a pair of spacing discs 32 and 33 on the other side, these discs 30, 32 and 33 having openings through the centers thereof accommodating the enlarged section 15' of the shaft. Another disc 34 is provided with an opening in the center for the accommodation of the shaft section 15' and is clamped tightly against the outer disc 33 by the screw 26 and the disc 27. In the particular embodiment shown, the disc 34 is clamped against the outside of the holding member 10, the latter having a central opening at the bottom which is smaller than the disc 34 but it is understood that the disc 34 may be of small enough diameter to fit within the opening formed in the bottom of the holding member 10 with its outer surface clamped tightly against the disc 27, since the spacing discs 32 and 33 are sufficient to avoid the rubber-like holding member 10 coming in contact with and deadening the gong 11.

In the particular embodiment shown the retaining and guiding means 17 is carried by a disc 35 which is also provided with an opening for threading the same over the shaft section 15' and this disc 35 is provided with a lug 36 extending toward the inner end of the cylinder 12 and engaging a holding recess 37 formed in the end surface thereof. By this means the retaining and guiding means 17 is caused to rotate with the cylinder 12, the two being thereby locked together.

In the particular embodiment shown the gate 19 is carried by a disc 38, the latter being disposed between the disc 35 and the inner end of the cylinder 12. This disc 38 has a section 39 removed from the periphery thereof for the purpose of clearing the holding lug 36 of the disc 35 and for the purpose of providing limited rotary movement of the disc 38 with respect to the cylinder 12 and the disc 35 to enable the gate 19 to be operated to either of its two positions of operation. The side walls 40 of the recess or removed section 39 form stops for engaging the lug 36 in the two operative positions of the gate 19 so that when one of the walls 40 is in engagement with the lug 36 the gate is in the open position and when the other side wall is in engagement with the lug 36 the gate 19 is closed. In the particular embodiment shown the disc 38 and the gate 19 are integrally formed, the gate 19 being carried by a lug 19' extending axially from the periphery of the disc 38. A finger operating piece 41 is turned up radially and outwardly of the periphery of the disc 38 from the lug 19' to form ready means for moving the gate 19 to either of its operative positions.

The cylinder 12 is journaled or swiveled on the shaft 15, 15' for movements independently of the holding member 10 and the shaft. It is swiveled at its outer end on the screw head of the shaft section 15 and it is swiveled at the inner end by being provided with a central opening accommodating in a swiveling manner the enlarged section 15' of the shaft. There is disposed between the disc 39 and the disc 35 a leaf spring member 43, the latter engaging on its convex side the disc 39 and engaging on its concave side at outer ends thereof the disc 35. By this means the disc 35 and disc 38 are held in assembled relation with respect to the cylinder 12 and the cylinder together with the discs 35 and 38 may be rotated about the shaft and against the friction entailed by the pressing of the leaf spring 43 against the inner end thereof. In order to prevent the ac-

cidental movement of the disc 38 and the gate 19 from one position to the other, the disc 38 may be provided with friction lugs or bosses 45 on the surface thereof adjacent the end of the cylinder 12, these lugs frictionally engaging the end of the cylinder to militate against such accidental movement either when the cylinder 12 is rotated independently of the platen 2 or when the latter is rotated during the operation of the machine.

Two similar friction lugs or bosses 46 are provided on the surface of the disc 35 for engaging the disc 38 and thereby tending to brake the movement of the disc 38.

When the platen knob 3 is of a dimension different from the interior diameter of the holding member 10 as, for example, when the diameter of the knob 4 is smaller than the interior diameter of the holding member 10, it is desirable to provide an adapter to adapt the device 5 to this particular machine knob. In Figs. 9 and 10 is shown such an adapter. This adapter is indicated at 50. This adapter 50 may be made of any suitable material and preferably of a flexible and resilient material as of rubber, synthetic or natural. This adapter has an exterior diameter equal to or slightly less than the internal diameter of the holding member 10 and, like the holding member 10 which has a holding flange 10', is provided with a holding flange 50' for engaging the side of the platen knob to hold the device 5 firmly on the knob.

In the embodiment of Figs. 11 to 14 the spiral track member 12' comprises a spiral track structure 63 the turns of which, instead of being arranged screw-like are formed coplanar about the axis of the shaft 3. The member 12' and its track are somewhat diagrammatically illustrated. The inner end of the track which is disposed adjacent an assembly shaft 67 is closed, while the other end of the track which is disposed at the peripheral surface of the member 12', is open as indicated at 66. The turns of the track 63 or the chamber track 63' thereof therefore spirals about the shaft 67 from the inner end 64 outwardly and radially in turns which gradually increase in diameter. A scale similar to that on the indicator member 12 of Fig. 1 is applied to the front surface 62 of the indicator member 12', this scale following the track 63, 63'. The zero mark of this scale is indicated at the outer end of the track at 66 and in the particular embodiment shown this scale runs up to eighty divisions. The metallic ball indicator 14 traverses this track when the indicator spiral track member 12' is rotated and the member 12' may be adjusted at the beginning of the typing of the page to give the signal at any point in the page desired for arresting the typing operation. For the purpose of adjustment, the indicator member 12' may be swiveled by hand as 60 by engaging the knob 68 on the front surface and rotating the member to bring the ball weight indicator 14 to the desired scale number or division on the scale indicated in Fig. 12, similarly as described with respect to the embodiment of Figs. 1 to 8. As the typist types the page the rotation of the platen 2 and the shaft 1 rotates the member 12' through the friction drive formed in part by the spring member 43 engaging the disc disposed about the shaft 67 and at the inner surface of the gong 11'. There is some friction also between the bolt head on the shaft 67 and the front disc side of the member 12', this frictional clutching means enabling the rotation of the member 12' independently of the shaft 3 to 70 adjust the position of the ball indicator 14 in

the spiral track. As the typist progresses with the typing of the page the scale on the front side of the member 12' indicates the position of the indicator ball at all times so that the typist by glancing at the scale can determine roughly how much farther down the page the typing is to be continued. Finally, the ball indicator 14 rolls out of the open end 66 of the track on to the inner surface of the gong 11', either to deliver a sound signal to the typist when the ball first falls upon the gong, or the continued typing operation causes a sound to be produced by the ball 14 vibrating or being jostled upon the gong. For facilitating the reentry of the track through the open end 66 by the ball 14, the outer end wall of the track is turned outwardly as indicated at 65 towards the gong 11' to form the guide or scoop for assuring the reentry of the track upon the member 12' being rotated counterclockwise. A stop 70 is provided about a third of a revolution from the open end of the track to prevent the ball member from becoming lodged or wedged between the wall of the track and the inner surface of the gong 11'.

The ball element 14 and its signal function may be discontinued at the will of the typist. This is effected by means of a screw element 69 which is screw-threadedly attached to an opening in the front disc 62 of the member 12', this screw-threaded opening being in line with the outer portion of the track chamber 63' just in advance of the opening 66 as illustrated in Figs. 12 and 14. This screw projects into the chamber at this point far enough to block the exit of the ball indicator 14 through the opening 66 and by engaging the knurled head of the screw 69 the typist may withdraw the screw until the inner end clears the path of the ball indicator 14.

The means 10 for holding the indicator in a readily attachable and detachable manner may be similar to that of the embodiment of Figs. 1 to 8. Spacing means 60 are provided between the gong 11' and the member 10 sufficient to cause the latter to clear the gong 11' and thereby avoid deadening of the sound of the gong. The shaft 67 may be generally similar to the shaft 15 of the embodiment of Figs. 1 to 8 but it is understood that the mounting of the indicator member 12' and the gong 11' is purposely shown diagrammatically since any suitable mounting of the elements 10, 11' and 12' may be provided.

This embodiment has the advantages of being more compact and of being less susceptible to vibrations and shocks during the typing operation and therefore more accurate in indication and signaling means.

It is understood that the indicating means 12 and 12' of the invention may be used with any other form of signaling than that shown in the drawings. For example, the gravity indicator member 14 may be utilized to operate a visual signal or a sound signal of any other character than that indicated. For instance, the gravity indicator member 14 may be utilized to close an electric circuit when it passes out of the open end of the track, which circuit controls a suitable indicator or sound signal through electrical means.

Fig. 15 illustrates a modification of the structure of the indicator member 12' of Figs. 11 to 14. In this embodiment the spiral track is formed by a pair of disc members 75 and 76 which are provided with complementary spiral tracks on their opposing sides for the accommodation of the ball indicator 14. The complementary spiral track 78

on the inner surface of the disk 75 is shown at 77 and the corresponding complementary spiral track on the disk 76 is shown at 78. The two discs are mounted on a shaft 79, which shaft may be similar to the shaft 67. In the particular embodiment shown these discs are spaced from each other by a sleeve 80 and in this embodiment this sleeve 80 is formed in two halves, one half being integral with the disk 75 and the other half being integral with the disc 76. The disc 75 is provided with a hub 68' similar generally to the hub 68 of Fig. 14, and this hub 68' is preferably knurled to provide a friction grip for the fingers in rotating the indicator unit 74 for adjustment 15 at the beginning of the typing of a page. Each of the complementary spiral tracks 77 and 78 is provided with a closed end adjacent the hub which together form the stop at the inner end of the track for the ball, this stop corresponding to 20 the stop 64 of Figs. 12 and 13. At the outer end or in advance of the outer end of the spiral track, which end is disposed at the periphery of the discs 75 and 76, are disposed complementary guides 81 and 82 which project slightly beyond 25 the peripheries of the discs and towards the gong 11' for the purpose of guiding the ball back into the groove from its position on the gong. These complementary guides or scoops may be formed integrally with the discs 75 and 76, which are 30 made of transparent material as, for example, a transparent plastic. These guides 81 and 82 not only extend in a direction toward the gong 11' but also in the direction of the spiral track at its outer end so as to facilitate the guiding of 35 the ball indicator into the track as the indicator member 74 is rotated by the fingers.

This embodiment of Fig. 15 has the advantage over the embodiment of Figs. 11 to 14 in that a larger and heavier indicator ball 14 may be used on an indicator member of the same diameter and same number of spiral track turns.

In the embodiment of Figs. 1 to 8 I have illustrated the spiral track indicator member 12 somewhat diagrammatically for the purpose of illustrating the purpose of the principle of the invention. In Fig. 16 I have illustrated this indicator member as being formed of a transparent cylinder 85 as, for example, being made of a transparent plastic material. The spiral track is 45 formed by a separate spirally constructed member 86, which member is assembled on the inside of the cylinder 85 after the latter is formed. This cylinder 85 may be formed with one end closed. The spiral track member 86 may then be inserted 50 lengthwise in the cylinder and thereupon the end disc 85' may be assembled and fastened to the end of the cylinder 85, this end disc 85' preferably being, but not necessarily so, of the same material of which the cylinder 85 is formed. In the 55 particular embodiment shown, the spiral member 86 which, together with the inner surface of the cylinder 85, forms the spiral track, is formed of wire of suitable material and dimensions. The outer end of the spiral member 86 is provided 60 with a bent end 22' which corresponds to the stop 22 of Fig. 3 for preventing wedging of the ball indicator 14 at the outer end of the track. This structure of Fig. 16 has advantages from the 65 standpoint of quantity production.

In Fig. 17 I have illustrated a modified means for readily attaching and detaching the indicator to most any make of typing machine on the market. This modified holding means comprises a flexible holding member 90, which is similar to the flexible holding members 10 described above.

Instead, however, of the disc 27 of Figs. 1 to 8 which is clamped to the shaft 15, I have here illustrated a winged disc-like member 91, the inner part 92 of this winged member being in the form of a disc which is clamped tightly against the spacing means as, for example, the discs 32, 33 and 34 of Figs. 1 to 8, or otherwise anchored to the shaft 15, 67 or 79. The outer part of this member 91 is formed of a multiplicity of blades 93, in the particular embodiment shown there being four, which are formed integrally with the inner part 92 and are preferably equally and uniformly spaced thereabout. These wings or blades 93 extend outwardly from the part 92 in both a composite radial and axial direction, that is, these wings 93 flare from the inner part 92 towards the typing machine. The outer ends of these wings or blades 93 thus form gripping parts for engaging the outer end surface of the knob or head 4. On certain makes of typing machines these knobs are as shown in Fig. 3, in other types the knob is formed with an outer central boss-like part of larger dimensions than that indicated in the head or knob 4 of Fig. 3, and the structure of the member 91 readily accommodates itself to the different types of knobs on the different makes of typing machines on the market. In Fig. 17 I have shown in dotted lines a modified knob or head 4' which has a central boss-like portion 94 of larger length or depth than that indicated on the corresponding knob or head 4 of Fig. 3.

What I claim is:

1. An attachment for a typing machine having a rotative platen, comprising fastening means which is readily attachable to and detachable from the platen, a member rotatable with and independently of said fastening means and having a spiral track adapted to accommodate an indicating member, an indicating member disposed in and wholly supported by said spiral track and means operated by said indicating member to indicate when the indicating member reaches a predetermined point in said spiral track.

2. An attachment for a typing machine having a rotative platen, comprising attaching means for ready attachment to and detachment from the platen, a cup-shaped gong, an indicator member rotatable both with and independently of said platen, said member having a spiral track disposed about the axis of the platen, a metallic ball traversing said spiral track during the rotation of the platen, and said gong being positioned to be engaged by the ball when it reaches one end of the spiral track.

3. An attachment for a typing machine having a rotative platen, comprising attaching means for ready attachment to and detachment from the platen, a cup-shaped gong, a hollow indicator member rotatable both with and independently of said platen, said member having a spiral track disposed therewithin and disposed about the axis of the platen, a metallic ball traversing said spiral track during the rotation of the platen, and said gong being positioned to be engaged by the ball when it reaches one end of the spiral track, said indicator member having a scale which follows the spiral track and being of transparent material whereby the ball is exteriorly visible in the track.

4. An indicating means for the platen of a typing machine comprising a hollow member rotatable with the platen of the typing machine and having therewithin a spiral track adapted to be traversed by an indicator disposed therein, an in-

dicator in said track, and said member being of transparent material whereby the indicator is exteriorly visible.

5. An indicating means for the platen of a typing machine comprising a member rotatable with the platen of the typing machine and having a spiral track adapted to be traversed by an indicating member, an indicating member disposed in said track and following the same by gravity in said track and on the indicating member as the member is rotated and signal means operated by said indicating member when it reaches a certain point in the spiral track.

15 6. An indicating means for the platen of a typing machine comprising a member rotatable with the platen of the typing machine and having a spiral track adapted to be traversed by a ball indicator disposed therein, a ball in said track, a gong, and said gong being positioned to be engaged by the ball when it reaches one end of the spiral track.

25 7. An indicator means for a typing machine having a platen comprising a support rotatable with the platen, a transparent indicator member rotatable with the platen and support, said transparent member having a spiral track in the interior thereof adapted to accommodate a cooperating indicating member, an indicating member in said track, said cooperating indicator member following said spiral track by gravity as the platen rotates, and an indicating scale on said member adjacent said spiral track.

30 8. An indicator means for a typing machine having a platen comprising a support rotatable with the platen, a transparent indicator member rotatable with the platen and support, said transparent member having a spiral track in the interior thereof adapted to accommodate a cooperating indicating member, an indicating member in said track, said cooperating indicator member following said spiral track by gravity as the platen rotates, an indicating scale on said member adjacent said spiral track, and means giving an indicating signal when the cooperating indicating member reaches one end of said spiral track.

35 9. In an indicator attachment for the platen of typing machines, the combination of means for fastening the attachment to rotate with the platen, a member rotatable with the platen and comprising a spiral track adapted to accommodate a metallic ball traversing said spiral by gravity as the platen rotates, a metallic ball in said track, said spiral track having an open end, and 40 55 a gong having a signal part disposed below the open end of said spiral track whereby said ball drops upon said signal part when it reaches the open end of the spiral track.

45 10. In an indicator attachment for the platen of typing machines, the combination of means for fastening the attachment to rotate with the platen, a member rotatable with the platen and comprising a spiral track adapted to accommodate a metallic ball traversing said spiral by gravity as the platen rotates, a metallic ball in said track, said spiral track having an open end, a gong having a signal part disposed below the open end of said spiral track whereby said ball drops upon said gong part when it reaches the open end of the spiral track, said member being of elongated form with the spiral track disposed about the axis thereof and progressing axially therealong with the inner end of the spiral being the open end.

50 70 11. In an indicator attachment for the platen of

typing machines, the combination of means for fastening the attachment to rotate with the platen, a member rotatable with the platen and comprising a spiral track adapted to accommodate a metallic ball traversing said spiral by gravity as the platen rotates, a metallic ball in said track, said spiral track having an open end, a gong having a signal part disposed below the open end of said spiral track whereby said ball drops upon said gong part when it reaches the open end of the spiral track, said member being of elongated form with the spiral disposed about the axis thereof and progressing axially therealong, with the inner end of the spiral being the open end, and a ball retaining tube disposed at the open end of the spiral track and between the open end and that part of the gong which is engaged by the ball.

12. In an indicator attachment for the platen of typing machines, the combination of means for fastening the attachment to rotate with the platen, a member rotatable with the platen and comprising a spiral track adapted to accommodate a metallic ball traversing said spiral by gravity as the platen rotates, a metallic ball in said track, said spiral track having an open end, a gong having a signal part disposed below the open end of said spiral track whereby said ball drops upon said gong part when it reaches the open end of the spiral, the turns of said spiral being coplanar, with the outer and open end thereof disposed adjacent the periphery of the member.

13. In an indicator attachment for the platen of typing machines, the combination of means for fastening the attachment to rotate with the platen, a member rotatable with the platen and comprising a spiral track adapted to accommodate a metallic ball traversing said spiral by gravity as the platen rotates, a metallic ball in said track, said spiral track having an open end, a gong having a signal part disposed below the open end of said spiral track whereby said ball drops upon said gong part when it reaches the open end of the spiral, the turns of said spiral being coplanar, with the outer and open end thereof disposed adjacent the periphery of the member, and means guiding said ball on to said gong and retaining the same against displacement.

14. An indicator attachment of the character set forth in claim 12 wherein the spiral track is formed by two spaced discs, said discs having complementary spiral grooves forming the spiral track.

15. An indicator attachment of the character set forth in claim 10 wherein the rotatable member comprises a transparent cylindrical casing and a separate spiral coil disposed in the cylinder and forming the track.

16. An indicator attachment of the character set forth in claim 10 wherein the rotatable member is provided with retarding means disposed at the open end of the track.

17. In an indicator attachment for typing machines, a means for readily attaching the attachment to and removing it from conventional typewriter platen knobs, comprising a flexible resilient cap adapted to surround the knob, and a disc-like member disposed in the cup, said disc-like mem-

ber having its peripheral parts axially flared from the central portion thereof toward the knob and adapted to engage the knob at points adjacent the periphery thereof.

5 18. An indicator attachment of the character set forth in claim 17 wherein the disc-like member is provided with a multiplicity of flaring blade-like members forming the periphery thereof and adapted to engage the knob.

10 19. In combination with an indicator attachment for typing machines, a means for readily fastening the attachment to and removing it from conventional typewriter platen knobs comprising a flexible resilient cup adapted to surround

15 and grip the knob and means for fastening the resilient cup to said attachment, said indicator attachment being rotatable independently of the resilient cup.

20 20. In combination with an indicator attachment for typing machines, a means for readily

fastening the attachment to and removing it from conventional typewriter platen knobs comprising a flexible resilient cup adapted to surround and grip the knob and means for fastening the re-

25 silient cup to said attachment, said last-named means comprising a disc-like member disposed on the bottom of the cup, the bottom of said cup being provided with an opening for the accom-
modation of a shaft.

30 21. An indicating means for the platen of a typing machine comprising a member rotatable with the platen of the typing machine and having a spiral track adapted to be traversed by a ball indicator disposed therein, a ball indicator in said

35 track, and a gong positioned to be engaged by the ball indicator when it reaches a predetermined point of the spiral track.

22. An indicating means for the platen of a typing machine of the character set forth in claim

40 21 wherein the rotatable member comprises a cylinder having a circular formed spiral wire mem-
ber disposed therein and forming with the inner surface of the cylinder said spiral track.

23. An indicating means for the platen of a

45 typing machine of the character set forth in claim 21 wherein the rotatable member is a cylinder hav-
ing a spiral track in the interior thereof, said cylinder having an opening on the underside thereof at said predetermined point for the indi-

50 cator to drop by gravity upon the gong and means for closing said opening.
